United States Patent Office.

BENJAMIN F. BEE, OF HARWICH, MASSACHUSETTS, ASSIGNOR TO THE NEW YORK TAP AND DIE COMPANY, OF NEW YORK CITY.

Letters Patent No. 77,951, dated May 19, 1868.

IMPROVED MACHINE FOR CUTTING ECCENTRIC-TAPS.

The Schedule referred to in these Letters Patent and making part of the same.

TO ALL WHOM IT MAY CONCERN:

Be it known that I, BENJAMIN F. BEE, of Harwich, in the county of Barnstable, and State of Massachusetts, have invented certain new and useful Improvements in Machinery for Cutting Taps and Dies; and that the following is a full, clear, and exact description of the same, reference being had to the accompanying drawings, in which—

Figure 1 represents a plan of a machine embodying my invention.

Figure 2 represents a front elevation of the same.

Figure 3 a rear elevation of the same.

Figure 4 an end view of the same.

Figure 5 an end view of the same, looking in a direction opposite to that in which fig. 4 was taken.

Figure 6 represents parts of the machine detached from the remainder.

Figure 7 represents a transverse section of a tap-blank of full size; suitable for being cut in the machine.

Figure 8 represents a section of the same tap-blank after being cut.

Figure 9 represents a corresponding section of the finished tap, after it has been cut and fluted.

The object of the improvements which constitute the subject-matter of the present patent is to enable taps and dies with eccentric-threads, such as are represented upon the tap at fig. 9 of the accompanying drawings, to be cut with rapidity, economy, and perfection. In such taps and dies, the portion of the thread extending backwards from each cutting-edge, *a*, towards the next succeeding cutting-edge, is eccentric to the axial line of the tap or die, and the mechanism which I am about to describe cuts such eccentric-threads by means of a rotating cutter, which, while revolving, is caused to approach and recede from the axial line of the blank as many times as there are cutting-edges to be made, while the blank is turned upon its axis and fed longitudinally past the position of the rotating cutter. The blank so eccentrically cut is subsequently fluted longitudinally, by a milling or planing-machine, so as to produce cutting-edges at the most protuberant parts of the threads.

In constructing such mechanism, I have made new combinations of sundry old members of machines for cutting metals, and have changed their form or construction, so as to adapt them to the particular object to be attained. My invention, therefore, consists of various new combinations of instrumentalities, the first of which consists of the combination of a rotating mandrel, to hold and turn the blank, a vibrating rotating cutter, to cut the groove between the threads, a cutter-arbor, inclined to the axis of the rotating mandrel, (for the purpose of enabling the cutter to cut an inclined thread,) a feed-screw, or equivalent mechanism, to determine the pitch of the thread cut, and a regulating-cam, for varying the position of the rotating cutter during the revolution of the mandrel, so as to impart the required eccentricity to the thread.

The special object of the second part of the invention is to guide the portion of the cutter that is operating upon the blank, so that it may run truly, notwithstanding the warped condition of the cutter, produced by tempering or other causes. This improvement consists of the combination of the rotating mandrel for the blank, with a rotating cutter, mounted upon an arbor that is free to play endwise in its boxes, with a guide for the side of the cutter to run against, and with a spring (or its equivalent, operating with a yielding pressure,) to keep the cutter constantly in contact with the guide, so that the guide determines the position of the acting portion of the cutter in its immediate vicinity.

The special object of the third part of my invention is to cause the cutter to vibrate in accordance with the form of the regulating-cam, and also to prevent it from running into the metal too deeply. This improvement consists of the combination of the rotating mandrel and rotating cutter, with a cutter-arbor inclined to the axial line of the mandrel, a regulating-cam, to determine the eccentricity of the cut made, and a weight or its equivalent, operating antagonistically to the cam, to exercise a yielding pressure, which causes the cutter-arbor to vibrate in accordance with the form of the regulating-cam, and at the same time prevents the cutter from running into the work.

The special object of the fourth part of the invention is to enable the rotating cutter to be readily set to its proper position, or at the required distance from the axial line of the mandrel and blank, so that taps of different sizes may be cut, and cutters of different diameters may be used, without changing the regulating-cam. This improvement consists of the combination of the rotating cutter and the regulating-cam, (that regulates its position) by means of connecting-mechanism, whose length is adjustable by means of a screw or its equivalent, for that purpose, so that the position of the rotating cutter relatively to the regulating-cam may be varied as required.

The special object of the fifth part of the invention is to cause the rotating cutter to cut progressively nearer to the axial line of the blank, as the blank is moved longitudinally past it, so as to cut the threads of tapering taps or dies. This improvement consists of the combination of the regulating-cam and the vibrating-tool support, with a variable connecting or combining-mechanism interposed between the two, and a directing-instrument for varying the effective length of said connecting-mechanism, as required, to cause the same protuberance of the regulating-cam to move the cutter to different extents; hence, as the cutting proceeds, the cutter is not moved as near to the axial line of the mandrel and blank during one revolution of the regulating-cam, as during the preceding revolution, so that the thread cut is tapering, although the protuberances of the cam do not vary.

The machine represented in the accompanying drawing embodies all my improvements in the best form which I have thus far devised, and is arranged for cutting taps. It has a bed or shears, A, supported on legs, b b', upon which the carriage C, which supports the tap-blank, is arranged to slide longitudinally. The bed also is provided at one end with a fixed head, d, that supports the cog-wheels that transmit motion to the moving members of the machine. The carriage has at one end a mandrel, B, that is constructed to turn in suitable boxes, f f, that project above the bed of the carriage; and this mandrel is provided at its inner end with a clamp-chuck, g, by which the head of the tap-blank D is secured to the mandrel, so as to be turned by it. The end of the carriage opposite the mandrel is fitted with a movable head, h, that supports the dead-centre e, upon which the small end of the tap-blank turns during cutting. The base of this movable head is provided with a longitudinal projection or feather, which slides in a groove formed in the bed of the carriage, so that the head is maintained in a central position on the carriage, although it may be moved towards and from the mandrel. The head h is clamped to the carriage by means of a screw-bolt. The bottom of the sliding head is inclined, and a wedge of the same inclination is inserted beneath the base, upon the upper surface of the bed of the carriage, so that the head may be adjusted by inserting the wedge more or less, to raise or lower the dead-centre, as may be required in setting the tap-blank in the machine. The tap-carriage C is moved to and fro by means of a feed-screw, E, which is arranged to turn in bearings at one side of the bed of the machine, and which is connected with the tap-carriage by means of a sectional nut, F, that is secured to the carriage, so that the carriage is screwed along by the turning of the feed-screw. One end of the shaft of the feed-screw E projects beyond its bearing at the end of the machine, and is fitted with a cog-wheel, G, by which the feed-screw is turned for the purpose of moving the tap-carriage. In order that the tap-blank may be turned upon its axis during cutting, the mandrel B is fitted with a cog-wheel, H, whose teeth engage with those of a pinion, H', that is secured to a sleeve, n, which turns in bearings f' f' upon the tap-carriage.

The bore of the pinion-sleeve n is traversed by a square shaft, J, which extends to one end of the bed of the machine, where it passes through a bearing. The end of the shaft J projects through this bearing, and is fitted with a cog-wheel, G', by turning which the shaft J, the sleeve n, the pinion H', and the mandrel B, with the tap-blank, are all turned. The pinion-sleeve n is arranged to slide longitudinally in its bearings, so that the pinion may be disengaged from the cog-wheel H, to permit the mandrel to be turned by hand during the operation of securing the tap-blank and removing it.

When the pinion is engaged with the wheel, it is held in place by a latch, I', which intervenes between a shoulder upon the pinion-sleeve and the side of the adjacent bearing f', and prevents the longitudinal movement of the sleeve.

The rotary cutter I, by which the screw-thread of the tap is cut, consists of a disk of steel, whose periphery is turned to the form of the groove between the threads to be cut, and is then cut into teeth like those of the rotary cutters of milling-machines for cutting metals, after which it is hardened and tempered. It is mounted upon an arbor, K, which is supported by the bearings, p p, of a tool-support, L, which is arranged to vibrate upon two centres, s s, so that the rotary cutter may move towards or from the axis of the mandrel and tap-blank, for the purpose of cutting the thread eccentric.

In order that the cutting-edge of the cutter may be maintained in its proper position, notwithstanding irregularities in the cutter, the arbor K is constructed to slide longitudinally in its bearings. A spring, M, is provided to act upon the end that is furthest from the cutter, and a fixed guide, N, is applied to the outer face of the disk of the cutter, as closely as possible to the cutting-edge; hence, the pressure of the spring causes the face of the rotary cutter to run constantly in contact with the guide, and permits the arbor to move so as to adapt itself to the irregularities which are generally found in such tools, while the part of the cutting-edge which is acting, being directed by the guide, runs truly, or thereabouts.

In order to cut the screw-thread on the tap-blank with the inclination corresponding with the pitch of the thread, the cutter-arbor K is inclined to the axial line of the mandrel and tap-blank, and in order that the same machine may be used for cutting taps of different pitches and diameters, the block O, to which the tool-support is pivoted by the centres s s, is secured to a bracket projecting from the bed of the machine, by means of screws t t, which pass through inclined slots in the centre-block O, so that centre-block may be adjusted upon the bed

of the machine, to hold the tool-support in different positions, as required to vary the inclination of the cutter-arbor to the axial line of the tap-blank.

The cutter-arbor is fitted with a belt-pulley, Q, to which the driving-belt is applied, and motion is communicated from this arbor to the feed-screw E, and to the shaft J that turns the mandrel B, by means of two pulleys, R R', a belt, S, and a train of cog-wheels, G, G¹, G², G³, G⁴, G⁵, G⁶, G⁷. One of the pulleys, R, which the belt S encircles, is secured to the cutter-arbor K; the other pulley, R', which the belt encircles, is secured to a sleeve, which turns freely upon a stud projecting from an arm, T, which swings upon the outer end of a stud, q, that is fixed to and projects from the head d of the bed of the machine. The pulley-sleeve is fitted with the cog-wheel G², whose teeth engage with those of a cog-wheel, G³, which is secured to a sleeve that turns upon the same fixed stud q that the arm T swings upon; hence the two cog-wheels G² G³ are always properly engaged; however the pulley R' may rise or fall to accommodate itself to the rising or falling of the cutter-arbor K, to which the first pulley, R, is applied.

In order that the belt S may be properly strained, to prevent it from slipping on the pulley the swinging arm T has a weight, U, applied to its end.

The sleeve of the cog-wheel G³ carries a second cog-wheel, G⁴, which gears into the cog-wheel G¹ that is secured to the shaft J, that transmits motion to the mandrel B. This shaft also is fitted with a second cog-wheel, G⁵, which imparts motion to the feed-screw E through the intervention of the cog-wheel G fixed to it, and an intermediate cog-wheel, G⁶, that turns upon a stud secured to the frame of the machine.

In order that the cutter may be raised and lowered, to cut eccentric-threads of the required form upon the tap-blank, a cam, V, is provided, having as many projections as there are to be cutting-edges upon the periphery of the finished tap. This regulating-cam is mounted upon a shaft, W, that turns in bearings upon the frame of the machine, and is fitted at one end with a cog-wheel, G⁷, that gears into the cog-wheel G¹, that is secured to the shaft J, which transmits motion to the mandrel B, so that the cam is turned with the mandrel. The relative proportions of the two cog-wheels, G⁵ G⁷, intervening between the shaft J and the regulating-cam V, are the same as those of the two cog-wheels H' H, that intervene between the same shaft J and the mandrel B, so that the tap-blank (which is held by the mandrel) and the regulating-cam turn with the same speed.

The regulating-cam is caused to regulate the position of the rotating cutter in the following manner: A strong frame, consisting of the standard, X, and the two arched bars, r r', is erected upon the frame of the machine, and a lever, Y, is pivoted to this frame by a pivot, u, in the vicinity of the standard X. The outer end of this lever is connected by an adjustable connecting-rod, Z, with a second lever, Y', whose inner end is formed into a head, v, that bears against the under side of the regulating-cam V, so that this bearing-lever, Y', and the first or upper lever, Y, are caused to vibrate as the regulating-cam revolves. The upper lever is connected with the vibrating-tool support L by a stud, z, upon the upper end of which the said upper lever bears, so that whenever a projection of the regulating-cam V depresses the bearing-lever, Y', and the upper lever, Y, the rotating cutter is forced nearer to the axial line of the mandrel and the tap-blank, and whenever the form of the regulating-cam permits the bearing-lever Y' and the upper lever to rise, the rotating cutter is permitted to rise or move further from the axial line of the mandrel and tap-blank.

In order that the rotating cutter may be moved from the axial line of the mandrel and tap-blank with certainty, so as to cut a thread corresponding with the eccentricity of the projections of the regulating-cam, the tool-support is provided with a weighted lever, A', which bears upon a stud, z', that is placed between the weight U' and the pivot w', that secures the lever to the tool-support, and whose lower end is sustained by the bed of the machine, so that the weight U', acting upon the tool-support antagonistically to the regulating-cam, tends to move the tool-support and the rotating cutter away from the axial line of the mandrel and tap-blank, and causes the bearing-lever to bear constantly against the regulating-cam V, and to apply itself to the surfaces of its projections.

The rotating cutter is thus acted upon by two forces, the one applied by the weight, and being a yielding pressure, that tends to move the cutter from the axial line of the mandrel and tap-blank, and the other being the positive force applied by the regulating-cam V, that, preponderating over the said yielding pressure, forces the cutter towards the axial line of the mandrel and tap-blank; and as the bearing-lever, Y', is constantly borne against the regulating-cam, the form of the cut produced by the rotating cutter is regulated by the form of the cam projections.

The weight U is made sufficient to overcome the tendency of the rotating cutter to run in to the work, and thus cut more deeply than it should; hence the weight U controls the cutter, and the lever A' on which it acts may be called the controlling lever.

In order that the same cam may be used to regulate the cutting of the threads of taps of different diameters, and may also be used to cut taps of the same size with cutters of different diameters, the mechanism that combines the rotating cutter with the regulating-cam is made adjustable in the following manner: The connecting-rod Z between the bearing-lever Y' and the upper lever Y, being fitted with a screw, d', which passes through a nut formed in the upper end of the connecting-rod, and bears upon the upper lever Y. By turning this screw the effective length of the connecting-rod, or the distance between the upper lever, Y and bearing-lever Y', can be adjusted as required to set the cutting-edge of the cutter at the proper distance from the axial line of the mandrel and tap-blank, and thus regulate the depth of cut. The fulcrum-stud z' of the controlling lever A' is also made adjustable by applying its lower end to a screw, d'', which turns in a base, g², whose lower end is grooved to rest upon the tap carriage C. The screw-head is provided with a capstan bar, e, by turning which the fulcrum-stud z' is raised or depressed, as required.

If the machine thus described be set to work upon a tap-blank, the latter will be turned by the mandrel B, the pitch of the thread will be determined by the feed-screw E, the form of the thread by the profile of the

periphery of the rotating cutter V, and the inclination of the cutter-arbor K, and the number of the cutting-edges and the eccentricity of the threads by the number and form of the projections of the regulating-cam V. If the machine be thus used without any change in the adjustment of the parts, the tap-blank cut will be of the same section throughout its length, or will be suitable for a plug-tap without taper.

In order to adapt the machine to cutting blanks for taper-taps, the mechanism for regulating the position of the rotating cutter is made self-adjusting, so as to cause the rotating cutter to recede from the axial line of the mandrel and tap-blank, as the blank is moved point foremost and longitudinally past the cutter. To this end the mechanism that combines the rotating cutter with the regulating-cam is made variable by pivoting the bearing-lever Y¹ to an elbow-lever, Y², which is constructed to swing upon a stud, q², secured to the bed of the machine, so as to raise and lower the fulcrum of the bearing-lever Y¹, the pivot that connects it with adjustable connecting-rod Z, and the upper lever Y. The upper end of the elbow-lever is provided with a cord, h², whose end is wound upon the extremity of the shaft W of the regulating-cam V. Hence, as the cam is turned, the cord h² is unwound from its shaft, and the elbow-lever Y² is moved to relax the pressure upon the bearing-lever Y¹, thereby permitting the rotating cutter to recede more and more, as the cutting proceeds, from the axial line of the mandrel and tap-blank, and to impart the required taper to the tap-blank. The form of the taper thus imparted may be varied, by varying the diameter and form of the extremity of the cam-shaft W, which directs the amount of variation, by determining the movement of the elbow-lever Y² through the cord, and is therefore the directing-instrument in the machine, and the taper may be caused to increase progressively, so as to impart a curved profile to the tap, by making the end of the cam-shaft, on which the cord is wound, of progressively greater diameter, thus giving it a conical or conoidal form.

As the same machine may be used for cutting plug-taps, or taps partly cylindrical and partly tapering, a stop, r², is provided to hold the elbow-lever Y², and consequently the fulcrum-pin of the bearing-lever Y¹, in a fixed position, when the directing-instrument is not varying it.

When the machine is used for cutting taps, the cutting proceeds from the point to the head of the tap. When the tap is thus cut it is taken from the machine and put into a milling-machine, by which it is fluted longitudinally so as to produce the cutting edges at the most protuberant parts of the tap-blank.

The combinations of mechanism existing in the machine thus described may be applied to the cutting of the dies for cutting the threads of screws. In such case the mandrel is provided with a chuck of suitable form and size to hold the die-blank to be cut, and the die-blank, previously bored to the approximate size of the interior of the thread, is applied to the chuck. The rotating cutter used must be sufficiently small to enter into the bore of the die, and vibrate therein, so as to cut the thread and if a guide be used, it should be placed on the inner side of the cutter, that is, on the side towards the driving-pulley Q, the spring being forked and arranged to bear against a collar on the arbor, so as to draw said arbor towards the spring, instead of pushing it, and thereby keep the inner face of the cutter running against the guide. For the purpose of getting rid of the cuttings, the parts of the machine may be so arranged that the rotating cutter is borne upwards by the action of the regulating-cam against the upper side of the interior of the die; and for the same reason the machine for cutting taps may be arranged to bear the rotating cutter upward against the under side of the tap-blank, instead of downwards upon its upper side.

The cutter described and represented in the drawings is adapted to cutting taps with V-threads; but threads of other forms may be cut in the same machine, by varying the profile of the cutter. The pitch of the thread may be varied by changing the feed-screw, or by varying the proportions of the wheels that impart motion to it in the manner usual in screw-cutting lathes, and the inclination of the arbor of the cutter to the axial line of the mandrel should always be such as to make the inclination of the plane of the cutter substantially the same as that of the thread of the screw.

When tap and die-blanks which are partly cylindrical and partly tapering are to be cut, the axial line of the two centres s s of the vibrating-tool support should be parallel to the axial line of the mandrel B. In such cases the distance between the cutter-arbor and the axial line of the centres must be less at one end than at the other, in order that the cutter-arbor may be properly inclined to the axial line of the mandrel and blank. As machines may be built in this manner for cutting blanks having threads of different inclinations, the variation in the inclination of the cutter-arbor may be obtained by fitting one or both of the centres s s to movable centre blocks, that are secured by screw-bolts to the tool-support, so that the parallelism of the axial line of the centres and mandrel may remain unchanged, while the distance between the cutter-arbor and the one or both centres may be varied, by moving one or both centre blocks, to vary the inclination of the cutter-arbor to the mandrel.

In the machine thus described a regulating-cam, having as many protuberances as there are to be cutting-edges in the tap is employed, but a regulating-cam, having a different number of protuberances, may be used if the speed of the cam-shaft W be correspondingly varied. Thus, for example, if there are to be four cutting-edges on the tap, a regulating-cam, with a single snail-formed protuberance may be used, if the wheels for imparting motion to its shaft be so proportioned as to cause the cam to turn four times for each revolution of the mandrel that carries the blank. I have also described the blank as being moved longitudinally past the rotating cutter, that being the arrangement which I prefer; but the mandrel-bearings may be fixed to the bed of the machine, and the cutter and its arbor may be mounted on a carriage and moved along the bed if deemed expedient.

Having thus described a machine embodying all my improvements, I declare that I do not claim the invention of any member thereof separately; but

What I claim as my invention, and desire to secure by Letters Patent, is—

1. The combination in one machine of the following instrumentalities, viz, the rotating mandrel to support the blank, vibrating rotating cutter, inclined cutter-arbor, feed-screw, and regulating-cam, formed and con-

structed to adapt them to the purpose to be accomplished, and all combined and operating in the machine substantially as before set forth.

2. I also claim the combination in a machine of the following instrumentalities, viz, the rotating mandrel, rotating cutter, mounted on a free arbor, cutter-guide, and spring, formed and constructed to adapt them to the purpose to be accomplished, and all combined and operating in the machine substantially as before set forth.

3. I also claim the combination in a machine of the following instrumentalities, viz, the rotating mandrel, rotating cutter, inclined cutter-arbor, regulating-cam, and weight, formed and constructed to adapt them to the purpose to be accomplished, and all combined and operating in the machine substantially as before set forth.

4. I also claim the combination in a machine of the following instrumentalities, viz, the rotating cutter, regulating-cam, and adjustable connecting-mechanism, formed and constructed to adapt them to the purpose to be accomplished, and all combined and operating in the machine substantially as before set forth.

5. I also claim the combination in a machine of the following instrumentalities, viz, the regulating-cam, vibrating-tool support, variable connecting-mechanism, and a directing-instrument, formed and constructed to adapt them to the purpose to be accomplished, and all combined and operating in the machine substantially as before set forth.

In testimony whereof, I have hereunto set my hand, this twenty eighth day of November, A. D. 1866.

BENJAMIN F. BEE.
